UNITED STATES PATENT OFFICE.

WALTER S. MOON, OF CANNELL, WASHINGTON.

SUBSOIL-PACKER.

1,071,075.

Specification of Letters Patent. Patented Aug. 26, 1913.

Application filed August 28, 1912. Serial No. 717,181.

To all whom it may concern:

Be it known that I, WALTER S. Moon, a citizen of the United States, residing at Cannell, in the county of Franklin and 5 State of Washington, have invented certain new and useful Improvements in Subsoil-Packers; and I do declare the following to be a full, clear, and exact description of the invention, such as will enable others skilled 10 in the art to which it appertains to make and use the same.

This invention relates to cultivators, and more especially to those which have a rolling motion, although as the packer bar in 15 the present case is made angular (preferably square) and rotates beneath the surface of the earth, and in a direction the reverse of that in which it would turn if it rolled upon the earth, the device is in effect 20 more in the nature of a subsoiler or harrow.

The object of the present invention is to produce a machine of this kind which will pack the soil after it has been plowed— one that is best adapted for dry farming dis- 25 tricts or soils of volcanic ash nature and inclined to blow and drift about in the wind.

Specifically, the object of the present invention is to produce a machine which will effect this end in the simplest manner, and 30 one which may be drawn by a pair of horses over two or more furrows of plowed land so as to act upon a strip of that width under ordinary circumstances.

These objects are carried out by construct- 35 ing the machine in a manner hereinafter more fully described and claimed, and as shown in the drawings wherein—

Figure 1 is a plan view of the machine complete, and Fig. 2 is a rear elevation thereof. Fig. 3 is an end elevation showing the parts in full lines with the packer shaft raised and in dotted lines with the packer shaft lowered. Figs. 4 and 5 are vertical sections taken about on the lines 45 1-1 and 5-5 of Fig. 3. Figs. 6, 7 and 8 are vertical sections taken on the lines 6-6, 7-7 and 8-8 of Fig. 1. Fig. 9 is a detail of the mechanism for supporting and bracing one of the beams, being taken on about 50 the line 9-9 of Fig. 6; and Fig. 10 is a further detail on about the line 10-10 of Fig. 6. Fig. 11 is a fragmentary detail, partly in

section, of the telescopic connection between the driving mechanism and the packer shaft.

In the embodiment of my invention illus- 55 trated in the drawings, two main wheels W have their hubs H connected with an axle A by backing ratchets so that the machine can turn corners in the usual and well known manner, and said axle becomes the power 60 shaft. As shown it is mounted in boxes J beneath a framework consisting of a front bar F, a rear bar R, cross bars C connecting said front and rear bars, and tie rods T also connecting said front and rear bars 65 alongside the cross bars and having nuts X on their extremities so that all parts may be tightened up. The tongue or pole P is connected with the framework in any suitable manner, and oblique braces O are preferably 70 employed to steady it; and the seat S may be mounted on the framework or on the pole as shown. When the driver is sitting thereon, a hand lever L moving over a quadrant Q stands within his easy reach. No novelty 75 is claimed for the parts thus far described.

The packer bar or shaft 1 in the present instance is a square rod of a length to extend across perhaps three ordinary plow furrows, although of course it might be 80 longer or shorter, and a rod of such length is provided at four points with collars 2 externally cylindrical so that they may fit within bushings or bearings 3 in the lower ends of beams 4 which are herein shown 85 as four in number and having straight and substantially horizontal front portions and downturned rigid rear ends 4' as best seen in Figs. 6 and 7. The beams are pivotally mounted at their front ends on a cross rod 90 5 supported in hangers 6 from the front bar F of the framework and are prevented from lateral motion by means of oblique braces 7 as best seen in Fig. 9; and said rod is connected with the rear beam R of the frame- 95 work by means of push bars 8 as best seen in Fig. 6. Said bars stand oblique, whereas the horizontal portions of the beams 4 stand only about horizontal when the packer shaft 1 is out of the ground; but when the 100 packer shaft is in the ground and the machine is working, the main portions of the beams 4 incline downward to about the same extent that the push bars 8 incline upward (see

dotted lines in Fig. 3) and therefore the strain thrown onto the cross rod 5 is well resisted by said push bars 8 and conveyed thereby to the main framework.

- 5 The adjusting mechanism for setting the packer shaft at any height desired or raising it entirely out of the ground, consists of a rock shaft 10 connected with a lever L and mounted in suitable journals in the 10 main framework, several arms 11 projecting radially therefrom, and several pairs of links 12 pivoted at their lower ends 13 to the beams 4 and having holes 14 in their upper ends so that a bolt or pin 15 may be 15 passed through one of them and through the outer end of the arm 11 and the rock shaft 10 thereby adjustably connected with the beams 4. When the operator manipulates the hand lever L and rocks the shaft 10, its 20 arms 11 through the links 12 cause the rise or fall of the beams 4 and hence raise the packer shaft 1 out of the ground or above the ground, or lower it into the same to adjusted positions therein.
- 25 The driving mechanism for causing the rotation of said shaft consists of a power gear 20 mounted on the main axle A and connecting with a driven gear 21 mounted on a counter shaft 22 journaled in suitable 30 bearings in the framework, a sprocket wheel 23 on the shaft connected by a chain belt 24 with a sprocket pinion 25 which is mounted in a suitable support 26 carried by hangers 27 from the main frame adjacent one main 35 wheel W, a telescopic shaft consisting of a tubular member 30 having a square bore and a solid member 31 made externally square so as to fit said bore, a universal joint 28 connecting one end of this telescopic 40 shaft with the stub shaft or hub 25' of the pinion 25, and a similar joint 29 connecting the other end of said shaft with the packer shaft 1 as best seen in Fig. 2. From this construction (which I might say is merely 45 illustrative of one means which may be employed to convey rotary motion from the main axle to the packer shaft) it will appear that when the machine is drawn forward, the rotary motion of the main axle is transmitted through the gears 20 and 21, and through the sprocket wheels and chain belt to the telescopic shaft, and by the latter to the packer shaft 1 which is caused to rotate in a direction the reverse of that in 50 which the main axle A is turning; and, as means are provided for raising the packer shaft into and out of the ground when desired, it is not necessary to provide means for checking the rotation thereof although 55 this could be accomplished by inserting a clutch in the driving mechanism as will be clearly understood without illustration or description.

60 The parts are by preference made entirely of metal excepting the beams of the

framework, the wheels and the tongue or pole. As at first suggested, the machine may be built as wide as necessary, but by preference it will have a packer shaft which will operate on at least three furrows of plowed 70 land.

In action the land is first plowed and then this packer is passed over it longitudinally of the furrows just made, with the packer shaft depressed to a point below the surface of the earth and rotating in a direction the reverse of that followed by the main axle as the machine progresses forward. The result is that the angles of a square packer shaft will pack summer fallow land, take 75 all weeds off or out of it, and lift the trash and clods to the surface, at the same time leaving a mulch beneath said surface where the wind will not strike it, thereby enabling the mulch to hold the moisture in the soil which is valuable in many sections of the country and especially in dry farming localities. Furthermore, the clods lifted to the surface prevent the soil from blowing 80 and drifting, and if they show weeds or 85 roots they may be removed later. Finally, the fact that the packer shaft rotates in what might be called a reverse direction is of additional advantage in that it causes 90 said shaft to clean itself, whereas otherwise the soil might stick to it. I have described and shown this shaft as square, but will claim it as angular because further experiments may show that a strictly square shaft 95 is not conducive of the best results in all places and under all conditions. These and other details of the invention may therefore be considered susceptible of modification, so long as the spirit of the invention is retained. 100

105 What is claimed as new is:

1. In a subsoil packer, the combination with the main framework, the wheels, and the power shaft; of a packer shaft, beams pivoted at their front ends to said framework and having downturned rear ends, devices connected with the latter for permitting the rotation of said packer shaft, means for adjusting the height of the packer shaft, a counter shaft rotated by and oppositely 110 to the direction of rotation of said power shaft, a stub shaft driven from said counter shaft, and a telescopic device connecting said stub shaft and packer shaft. 115

2. In a subsoil packer, the combination with the main framework, the wheels, and the power shaft; of a packer shaft, beams pivoted at one end to said framework, means for adjusting their other ends vertically, devices connected with the adjustable ends for permitting the rotation of said packer shaft, a stub shaft journaled in bearings carried by said main framework, a telescopic shaft, universal joints connecting the extremities 120 of said telescopic shaft with said stub shaft 125

and packer shaft respectively, and connections between the stub shaft and power shaft for rotating the former from the latter.

3. In a subsoil packer, the combination with the main framework; of a packer shaft, beams having downturned rear ends provided with bearings for said packer shaft, hangers depending from the front bar of said framework, a cross rod connecting said hangers and on which the front ends of said beams are pivoted, a push bar connecting said cross rod with the rear bar of the framework, a brace connecting each beam with said cross rod at a point on the latter remote from the point where the front end of the beam is attached thereto, means for adjusting the rear ends of the beams vertically, and means for rotating said packer shaft in said bearings.
4. In a subsoil packer, the combination with the main framework, the wheels, and the axle; of a packer shaft, beams having downturned rear ends provided with bearings for said shaft, hangers depending from the front bar of said framework, a cross rod connecting said hangers and on which the front ends of said beams are pivoted, a push bar connecting said cross rod with the rear bar of the framework, links rising from the rear portions of said beams and provided with holes, a rock shaft journaled in said framework and having arms adjustably connected with certain of said holes, a lever for adjusting the position of said rock shaft, and means for rotating the packer shaft.
5. In a subsoil packer, the combination with the main framework, the wheels, and the axle rotated by such wheels; of an angular packer shaft, collars secured thereon, beams having downturned rear ends provided with bearings in which said collars are journaled, pivotal connections between the front ends of said beams and the framework, links rising from the rear portions of said beams and provided with holes, a rock shaft journaled in said framework and having arms adjustably connected with certain of said holes, a lever for adjusting the position of said rock shaft, and means for rotating the packer shaft.
6. In a subsoil packer, the combination with the main framework, the wheels, and the axle rotated by such wheels; of an angular packer shaft, collars secured thereon, beams having downturned rear ends provided with bearings in which said collars are journaled, hangers depending from the front bar of said framework, a cross rod connecting said hangers and on which the front ends of said beams are pivoted, a push bar connecting said cross rod with the rear bar of the framework, links rising from the rear portions of said beams and provided with holes, a rock shaft journaled in said framework and having arms adjustably connected with certain of said holes, a lever for adjusting the position of said rock shaft, and means for rotating the packer shaft.

7. In a subsoil packer, the combination with certain of said holes, a lever for adjusting the position of said rock shaft, and means for rotating the packer shaft and its collars in said bearings.

8. In a subsoil packer, the combination with the main framework, the wheels, and the axle rotated by such wheels; of an angular packer shaft, collars secured thereon, beams having downturned rear ends provided with bearings in which said collars are journaled, hangers depending from the front bar of said framework, a cross rod connecting said hangers and on which the front ends of said beams are pivoted, a push bar connecting said cross rod with the rear bar of the framework, a brace connecting each beam with said cross rod at a point on the latter remote from the point where the front end of the beam is attached thereto, means for adjusting the rear ends of the beams vertically, and means for rotating said packer shaft and its collars in said bearings.

9. In a subsoil packer, the combination with the main framework, the wheels, and the axle rotated by such wheels; of an angular packer shaft, collars secured thereon, beams having downturned rear ends provided with bearings in which said collars are journaled, pivotal connections between the front ends of said beams and the framework, means for adjusting the rear ends of said beams vertically, a stub shaft journaled in bearings carried by said main framework, a telescopic shaft, universal joints connecting the extremities of said telescopic shaft with said stub shaft and packer shaft respectively, and connections between the stub shaft and axle for rotating the former from the latter.

10. In a subsoil packer, the combination with the main framework, the wheels, and the axle rotated by such wheels; of an angular packer shaft, beams pivoted at one end to said framework, means for adjusting their other ends vertically, devices connected with the adjustable ends for permitting the rotation of said packer shaft, a stub shaft journaled in bearings carried by said main framework, a telescopic shaft, universal joints connecting the extremities of said telescopic shaft with said stub shaft and packer shaft respectively, and connections between the stub shaft and axle for rotating the former from the latter but in opposite direction thereto.

11. In a subsoil packer, the combination with the main framework, the wheels, and the axle rotated by such wheels; of an angular packer shaft, beams pivoted at their front ends to said framework and having downturned rear ends, devices connected with the latter for permitting the rotation of said packer shaft, means for adjusting the height of the shaft vertically, a counter

shaft rotated by and oppositely to the direction of rotation of said axle, a stub shaft driven from said counter shaft, a telescopic shaft, and universal joints connecting opposite ends of said telescopic shaft with said stub shaft and said packer shaft respectively.

In testimony whereof I have hereunto set my hand in presence of two subscribing witnesses.

WALTER S. MOON.
